YARN CARRIER STOP CONTROL MECHANISM FOR STRAIGHT KNITTING MACHINES

Max Richter, West Reading, Pa., assignor to Textile Machine Works, Wyomissing, Pa., a corporation of Pennsylvania

Application March 9, 1935, Serial No. 10,169

7 Claims. (Cl. 66—126)

My invention relates to yarn-carrier stop-control mechanism for knitting machines, and particularly to means for effecting automatic operation of the yarn-carrier stops of straight knitting machines.

In a knitting machine of the so-called "straight", or "flat" type, as in a machine for knitting full-fashioned stocking blanks, the yarn is laid to the needles, and other knitting parts, 10 by carriers or fingers, which are mounted on carrier rods for movements of various sequences and distances in accordance with a given pattern of the fabric being knitted, as in effecting narrowing or fashioning stitches.

15 Stops, for controlling the longitudinal movements of the carrier rods, are ordinarily pivotally mounted on the narrowing head units for manual operation, consequently requiring a skilled operator to effectively control the machine to ensure a desirable product, or are mounted 20 for operation from the cam shaft by means which, by maintaining parts in constant operation, subjects them to excess wear, requires separate means for transmitting stop-selecting and 25 stop-actuating movements from the cam shaft to the stops, and has other disadvantages.

Among the objects of my invention are to avoid the disadvantages of manual operation of the stops, and to provide a device of improved automatic structure and operation therefor, as in features wherein the stops, instead of being pivotally, or rotatably, mounted for movement between operative and inoperative positions, are non-rotatably mounted, a single connection is 35 provided between the cam shaft and a stop selecting and operating means for effecting both the selecting and operating movements, parts heretofore allowed to operate continuously are replaced by parts which operate only as required, 40 a more flexible and effective pattern control is effected, wear of the machine parts is minimized, the number, weight and cost, of parts are reduced, and other advantages are obtained, as will herein appear.

45 Another object of my invention is to provide a device of the above-indicated character, and to render it simple and durable in construction, economical to manufacture and effective in its operation.

50 With these and other objects in view, which will be apparent from the following detailed description of the illustrative embodiment of the invention shown in the accompanying drawings, my invention resides in the novel mechanism and

means for operating the same, as hereinafter more particularly pointed out in the claims.

In the drawings:

Figure 1 is a fragmentary top plan view of a full fashioned knitting machine, showing the carrier end stop mechanism in accordance with the invention;

Fig. 2 is an enlarged vertical cross-sectional view of the knitting machine, shown in Fig. 1;

Fig. 3 is an enlarged vertical cross-sectional view, taken substantially along the line 3—3 of Fig. 1;

Fig. 4 is an enlarged plan view of the end stop mechanism constructed in accordance with the invention, taken substantially in the direction of the arrow "A" of Fig. 3;

Fig. 5 is a cross-sectional view, taken substantially along the line 5—5 of Fig. 4;

Fig. 6 is a detail view, taken substantially along the line 6—6 of Fig. 4;

Fig. 7 is a diagram of the leg blank of a full-fashioned stocking, together with a pair of pattern chains, as developed or opened out along straight lines in side elevation from their normal loop shape, indicating the positions along the blank at which the end stops are operated and the corresponding links of the chains by which such operations are effected;

Figs. 8 to 15, inclusive, are sequence plan view diagrams of the carrier rods and stops as disposed at positions corresponding to the positions indicated along the blank of Fig. 7;

Figs. 8a to 15a, inclusive, are end views of the corresponding Figures 8 to 15, inclusive; and

Figs. 8b to 15b, inclusive, are views similar to Figs. 8a to 15a, of the opposite ends of the devices of Figs. 8 to 15, inclusive.

The figures illustrate various parts of a "Reading" full-fashioned stocking-knitting machine embodying the mechanism and elements of my invention, in which, for clearness, only those parts of the various mechanisms necessary for an understanding of the invention are illustrated; the other parts and mechanisms, and the operation thereof, being well known in the art, as shown and described in the "Reading" Full Fashioned Knitting Machine Catalogue, copyright 1929, and published by the Textile Machine Works, Reading, Pennsylvania.

Referring to the drawings:

Vertical center frames 10, and end frames 12, support a longitudinally extending front rail 13, a back rail 14, a front bed 15 and a center bed 16 to constitute a framework or base upon which the

50

55

operating parts of the knitting machine are supported, as indicated in Figs. 1, 2 and 3.

A cam shaft 17, rotatably mounted on the frames 10 and 12, carries a series of cams, by which the various mechanisms are separately actuated; one series of cams imparting movement to the respective mechanisms to effect the cycle of operations of fabricating the main body of the fabric, and a second series of cams imparting the motion to said mechanisms to effect the narrowing or fashioning operations.

To axially shift the cam shaft, back and forth between its regular knitting and narrowing positions, a chain motion mechanism "C" is provided to coact with shifting cams 18, at intervals determined by the sequence of buttons 19 carried by a narrowing chain 20.

Narrowing heads N, operated by cams on the cam shaft 17, while the latter is in its shifted or narrowing position, operate to progressively decrease the strokes of the carrier rods by an end stop mechanism S, which is carried, and operated, by back spindles 23. Front spindles 24 actuate narrowing rods 25 to produce narrowing stitches.

The narrowing rods 25 are longitudinally slidably mounted in brackets 26, which are suspended from a front narrowing shaft 27. The shaft 27 is maintained parallel to a back narrowing shaft 28, by guide brackets 29, and moved upwardly and downwardly to permit narrowing fingers (not shown) to engage needles 30, through narrowing levers 32 pivotally mounted on the center frames 10, by a stud 33, Fig. 2. The levers 32 receive motion by engagement of rollers 34 thereof with cam members carried by the cam shaft 17, this action being transmitted to the shaft 27 through an intermediate link member 35.

The needles 30 are operated, through usual cycles, by needle levers 36 and presser levers 37, which receive motion from cams on the cam shaft.

The carrier rods, longitudinally mounted in brackets 38 fixed to the center bed 16, are longitudinally reciprocated, by the cam shaft 17, through intermediate linkage (not shown); this action imparting a corresponding movement to yarn carriers or fingers 39 carried by the rods, by which yarn is fed to the loop forming elements.

The formation of loops is effected by cooperation between the needles 30, sinkers 40 and dividers 42. Forward and retracted movements of the sinkers and dividers are, respectively, effected by jacks 43 and a catch bar 44. The jacks are slurred forwardly in succession to transmit similar motion to the sinkers, by means of slur cams 45 carried by reciprocating cock boxes 46.

Forward and backward movement of the dividers, and retraction of the sinkers, are effected by the catch bar 44, through shifting arms 47 and 48 operated by a cam actuated back catch lever 49. A shaft 50 serves as a carrier for both the arm 48 and the lever 49. Vertical movement is imparted to the catch bar 44 by a front catch shaft 52, and an intermediate linkage, which is controlled by a front catch lever 53.

Intermittent rotation of a control shaft 54, constituting part of a selector mechanism for controlling the operation of the end-stop mechanisms S, is produced by the structure shown in Fig. 3; operation of the shaft being controlled by buttons 55 on a variable pattern device, or chain, 56 which is carried, and operated, by the chain motion mechanism C, Fig. 1. Operative positioning, by the chain 56 of one of the but-

tons 55, draws a rod 57 to the left, as viewed in Fig. 1, which action imparts a clockwise movement to a support lever 58 that is pivoted to the front rail 13, by a bolt 59. This action moves the support lever 58 from beneath a horizontal arm of a lever 60, pivoted on a shaft 61, whereupon a spring 62 causes a cam follower 63, rotatably carried by the lever 60, to follow the contour of a cam 64.

The cam 64, by reason of its contour, racks a ratchet wheel 65 through a distance equal to the pitch of a tooth thereof during each operation, this action imparting a clockwise movement to the control shaft 54 to which the ratchet wheel is fixed, see Fig. 3. Movement of the lever 60, effected by the cam 64, is transmitted, through the ratchet wheel 65, to the control shaft 54, by a pawl 66 carried on a member 67, which is loosely mounted on the control shaft 54, and connected to the lever 60 by a link 68.

The spring 62, attached to the back rail 14 by a hook 69, is also attached to an extension of the member 68, thereby acting either, to cause the roller 63 to follow the contour of the cam 64, or to keep the same out of engagement therewith, by holding a lower portion of the lever 60 in contact with the support lever 58, in accordance with the sequence of the buttons 55 on a variable pattern device or chain 56. Variable pattern devices or end stop chains 70 and 71 are operated in conjunction with the control shaft 54, by wheels 72 carried thereby; the chains being held in operative position relative to the wheels 72, by idler pulleys 73.

In accordance with the invention, I provide a unit S, comprising a plurality of slideable end stops 74, carried by each of carrier nuts 75 which are carried, and operated, by the spindles 23 of the narrowing heads N. The slideable stops 74, on the left-hand end of the machine, as viewed in Fig. 1, in the present instance, control the extent of travel to the left of carrier rods 2, 3, 5 and 7, but they may be operated to control all of the carriers in preselected order, as desired. The travel, of carrier rods 1 and 4 to the left, is determined by respective stop members 74 which in this case are not lifted; see diagrammatic views of Figs. 8 to 15, inclusive.

The above-mentioned order of operation is reversed during movement of the carrier rods 1, 3, 4, 6 and 8 to the right, the strokes of which are terminated by slideable stop members, but these stop members may also be operated to control all of the carriers. The travel of carrier 2 is also controlled by a stop, which in this case is not lifted on the right side. Thus, in the above arrangement, the stops, for the respective carrier rods are carried by the narrowing heads and lifted at the end of the machine corresponding to the end of knitting section at which the carriers are positioned when out of operation.

The stops 74 are normally held in their respective operative positions by tension springs 77 secured thereto and to the carrier nut 75. The carrier rods 1, 2, 3, 4, 6 or 8, moving to the right, are selectively stopped by stop elements 78 adjustably positioned in lower portions of sliding stop members 74. When the yarn carriers are operating to feed yarn to the loop forming elements, the strokes of the carrier rods are controlled by the end stops aligned therewith; the carriers being placed out of operation by raising the respective end stops 74 and permitting the carrier rods to pass therebeneath, as illustrated in Fig. 5.

5 Hooks 74a are provided, at the upper ends of the slideable stops, to facilitate manual operation thereof; mechanical operation being automatically effected, in accordance with my invention, substantially as illustrated in Figs. 3, 4 and 5.

An axle 79, supported in an upright extension of the carrier nut 75, carries motion-transmitting members or levers 80, which are free to oscillate thereon. As shown in Fig. 5, one end of each 10 lever 80 coats with a shoulder 74b on a corresponding end stop, which is held in yielding engagement with its lever 80, by its spring 77; the opposite ends of the levers 80 cooperating with buttons 82 carried by a rotatable member 83.

15 The member 83 is rotatably mounted in bearings in the upright extension of the carrier nut 75, intermittent rotation thereof being effected by a pawl 84 pivotally mounted on a bracket 85, which is loosely carried by an extension of the 20 axle of the member 83. The pawl 84 operates the member 83 through a ratchet 86 secured to the member 83. A pin 87, extending from the bracket 85, Fig. 4, is held in engagement with a plate 88 by a spring 89, which is anchored to the 25 carrier narrowing nut by a stud 90.

Any operative movements of a lever 92, pivotally supported on a shaft 93 in a bracket 94 attached to the stabilizing bar 95, which are effected by the coaction of high buttons on the 30 chain 70 with a roller 96 of the lever 92, will transmit a corresponding oscillatory movement to the pin 87, and operate the pawl 84 through the plate 88 secured to the lever 92 by bolts 97.

Reverse movements, of the rotatable member 35 83, are prevented by a lock dial 98 and an index plate 99. The dial 98 is secured to the member 83, and the index member 99, held in yielding engagement therewith, is secured to the carrier narrowing nut structure, as illustrated in 40 Figs. 4 and 6.

As indicated in Figs. 2, 3, 4 and 5, which show the mechanism at the right-hand end of the machine, as viewed in Fig. 1, on which side the fingers 39 on carrier rods 1, 3, 4, 6 and 8 are placed 45 out of operation, buttons on the member 83, the motion transmitting members 80, and the slideable end stops 74, are disposed in line with the respective carrier rods. The buttons 82 are disposed about the member 83 in positions to operate the 50 slideable end stops transversely to the paths of movement of the rods in a desired order.

The links of the control chains 70 and 71 determine the sequence of operation of the end stops, which limit the travel of the carrier rods 55 1 to 8, inclusive, in both directions, or operate in conjunction with various auxiliary stop mechanisms to limit the travel of the carriers during the production of a stocking leg blank. The control chains 70 and 71 as indicated in Fig. 7, 60 control the action of the end stops of the machine from a line 121, in advance of the first course knitted in the welt, to the course 122 of the heel tabs T, T.

The stocking leg blank L extends from the top 65 edge 123 of the folded welt portion W, to the course 122 of the heel tabs T. The line 124 indicates the first course of loops of the welt W in an open state.

Prior to knitting the first course of loops 124 70 of the welt W, the control chains 70 and 71 are operated for a distance corresponding to the distance 125, which extends from the line 121 to the course 124 of the welt W, to raise right and left end stops 74, see Figs. 8, 8a and 8b, which 75 normally control the end movement of carrier 3.

At this time, however, the travel of carrier rod 3, which is used to lay yarn to the welt W, is controlled by one of the above mentioned auxiliary stop mechanisms, so that the end stops may be reset from the inner position to the outer position 5 of their travel.

The end stops 74 for carrier rod 3 are maintained in a raised position through a distance 126, which extends from the course 124 to a course 127, at which latter position the control 10 chains operate to release the right and left stops to limit the travel of carrier rod 3, see Figs. 9, 9a and 9b. The right and left stops for carrier rod 3 are maintained in this position through a distance 128, or from the course 127 to a course 129 where the right stop 74 is raised through a movement of the control chain 70 to remove the finger 39 of carrier 3 from the knitting field, see 15 Figs. 10 and 10b.

At this position, in the production of the leg 20 blank L, one or more carriers are drawn into the knitting field; in the present instance the fingers of carrier rods 1, 2 and 4 of the alternating mechanism are operatively positioned to lay yarn to the needles 30, see Figs. 10, 10a and 10b. The end stops are maintained in this position through a distance 131, from the line 130 to a line 132, at which latter position right end stops 74 for carrier rods 1 and 4 are raised, through 25 control chain 70, so as to position the fingers of carrier rods 1 and 4 out of the knitting field, see Figs. 11 and 11b. This position of the end stops is maintained through a distance 133, which extends from the line 132 to a line 134, at which latter position right end stops for carrier rods 1 and 4 are released through the control chain 70, 30 see Figs. 12 and 12b.

The end stops are maintained in this position for a distance corresponding to the distance 134, or from the course 134 to a course 136, at which latter position the control chain 70 is again operated to raise the right stop for carrier rod 3, which is to be removed from the knitting field, 40 see Figs. 13 and 13b. This position is maintained for a distance 137, extending from the course 136 to a course 138 where the right stop for carrier rod 6 is raised, by operation of the control chain 70 to remove the carrier from the knitting field, 45 see Figs. 14 and 14b. As indicated in Figs. 7, 14 and 14a, the stop for carrier rod 5 is raised, by 50 operation of control chain 71. This is the first movement of the stops controlled by chain 71, for a distance corresponding to a distance 142 which extends from the course 127 to a course 143.

The end stops are held inoperative through a 55 distance corresponding to the distance 140, which extends from the course 138 to the course 122 where the right end stops for carrier rods 4 and 6 are raised to remove the carriers to an inoperative position upon operation of the control chain 70, see Figs. 15 and 15b. The control chain 71 is operated to raise end stops for carrier rods 2 and 7, to permit removal of the carriers from the knitting field after operating through a distance 60 144, which extends from the course 143 to the course 122 of the stocking blank, see Figs. 15 and 15a.

The stops 74 are raised to lay out the carriers, 65 by means of the levers 80, and are released during the next movement of the drum 82, whereupon the levers affected drop upon supporting members 100. The supporting members 100 prevent the levers 80, and the stops therefor from dropping too far as the carrier rods are drawn from beneath 70 the stops.

It will be understood, that only those stops, necessary for the removal of a carrier, are raised and that normally the stops are in an operative position, or rest upon the rods of the carriers which are laid out of the knitting field, so that, as the carriers are drawn into the knitting field, the stops will either be in, or drop into an operative position to control the travel of the carriers. As shown in Figs. 7, 10 to 13, and 10a to 13a, inclusive, it will be seen that the control chain 11, although operating the same number of times as chain 70, does not always effect movement of the end stops which are controlled thereby, thus permitting selective operation of the slideable end stops 14 on the right and left sides independently of each other.

The plate 88 is of sufficient length to remain in contact with the pin 87 irrespective of the extent of travel of the carrier narrowing nut, as ordinarily occasioned during the narrowing process.

The buttons 82 are interchangeable, about the rotatable member 83, to provide flexible means for operating the slideable end stops, in accordance with any predetermined order.

In the above-described structure, the cam 64 and the cam shaft 17, being at the lower front portion of the machine, are located a substantial distance from the parts controlled and actuated thereby at the upper rear part of the machine, the latter parts being the chains 70 and 71 and their associated elements for selecting the sequence of operation of the non-rotative stops 14, and the members 83 having the buttons 82 thereon locally associated with the stops 14 for actuating the same, as selected by the chains.

A single means or linkage including the link 68, the cam follower 63 and the lever 60, is connected, at its upper rear end, to the pawl supporting lever 67. By this arrangement are obtained both the stop-selecting movements of the chains 70 and 71, and the non-rotative stop-actuating movements which are translated from the rotative movement of the cam shaft by the member 83, and associated parts. The above-mentioned single linkage is operatively connected, adjacent to its lower front end, to the cam 17, by the follower 63, to receive its actuating movement from the cam shaft, and to the chain 56, by the lever 60, the lever 58 and the buttons 55, whereby such actuating movement, translating the rotative movement of the cam shaft into the non-rotative movement of the stops, is controlled in accordance with a given pattern.

By adding links to the chains 70 and 71, withdrawing them from the chains, or varying their length, shape or height, and by similarly varying the buttons 55 of the chain 56, a wide selection of operation of the stops 14 may be effected, without the necessity of carrying in stock a number of expensive fixed-pattern cams to take the place of the chains 70 and 71. Also, since the above-mentioned single means, or linkage, represented by the link 68, the cam follower 63 and the lever 60, is only intermittently operated, and has no part which is constantly moving, substantially minimum operation and wear of the parts are ensured.

Other features of the invention contributing to long life of the parts, ensuring effective operation and design, and providing further advantages, include the feature wherein the follower 63 engages the cam 64 at only a single point or position on the periphery thereof at any one time, as distinguished from an eccentric, in

which a follower frictionally engages a cam-like member entirely about its periphery; the feature wherein the lever 58 at times prevents the imposition on the cam 64 of the force of the spring 62 and the friction of the follower 63, and the arrangement whereby the cam 64 and the follower 63 are moved relatively between operative and inoperative positions with respect to each other, to prevent the wear accompanying constant engagement of such parts.

The improvements specifically shown and described, by which the above-described results are obtained, can be modified in various ways, without departing from the invention as herein set forth and claimed.

I claim:

1. In a straight knitting machine, carrier rods, a pattern device, a stop support, elongated stops for the carrier rods longitudinally movably mounted on the support, means rotatably mounted on the support for detachably receiving actuating elements providing at least one each for any selected number of stops and each for mounting at any one of a plurality of positions for longitudinally actuating the stops, and means operating between said rotatably-mounted means and the pattern device for actuating the rotatably-mounted means to effect the longitudinal movement of the stops.

2. In a straight knitting machine, carrier rods, a pattern device, a stop support, elongated stops for the carrier rods longitudinally movably mounted on the support, means including members movably mounted on the support cooperating with the stops for longitudinally moving the stops transversely to the rods between active and inactive position relative to the carrier rods, means rotatably mounted on the support for detachably receiving actuating elements provided at least one each for any selected number of said movably mounted members and each for mounting at any one of a plurality of positions for actuating said movably mounted members to longitudinally move the stops, and means operating between said rotatably-mounted means and the pattern device for actuating the rotatably-mounted means to effect the longitudinal movement of the stops.

3. In a straight knitting machine, carrier rods, a pattern device, a stop support, stops for the carrier rods movably mounted on the support, means including levers pivoted on the support about axes transverse to the rods cooperating with the stops for moving the same between operative and inoperative positions relative to the carrier rods, means rotatably mounted on the support for detachably receiving actuating elements provided at least one each for any selected number of said levers and each for mounting at any one of a plurality of positions for actuating the levers, and means operating between said rotatably-mounted means and the pattern device for actuating the rotatably-mounted means.

4. In a straight knitting machine, carrier rods, a narrowing carriage, a pattern device, a bracket on the narrowing carriage, stops for the carrier rods mounted on the bracket, means including levers extending in the direction of the rods pivoted on the bracket cooperating with the stops for moving the same between operative and inoperative positions relative to the rods, means rotatably mounted on the bracket for detachably receiving actuating elements provided at least one each for any selected number of said levers

and each for mounting at any one of a plurality of positions for engaging the corresponding lever, and means operating between said rotatably-mounted means and the pattern device for actuating the rotatably-mounted means.

5. In a straight knitting machine, carrier rods, a narrowing carriage, a pattern device, a bracket on the narrowing carriage, elongated stops for the carrier rods longitudinally slidably mounted 10 on the bracket transversely to the rods, means including levers pivoted about axes transverse to the rods on the bracket cooperating with the stops for moving the stops between operative and inoperative positions relative to the carrier 15 rods, a drum rotatably mounted on the bracket having portions for detachably receiving buttons provided at least one each for any selected number of said levers and each for mounting at any one of a plurality of positions for actuating said 20 levers, a ratchet wheel secured to the drum, a pawl for the ratchet, and means operating between the pattern device and the pawl for actuating the pawl.

6. In a straight knitting machine, carrier rods, 25 a narrowing carriage, a cam shaft, a pattern device, a bracket on the narrowing carriage, elongated stops for the carrier rods longitudinally slidably mounted on the bracket transversely to the rods, the brackets having a slideway for receiving ends of the rods beyond the stops, rod contact members 30 adjustably mounted on the front sides of the stops, levers of equal lengths pivoted on the bracket each having an arm cooperating with the rear side of the corresponding stop for raising and lowering the stop, a drum 35 rotatably mounted on the bracket having portions for detachably receiving buttons provided at least one each for any selected number of stops

and each for mounting at any one of a plurality of positions for engaging another arm of the corresponding lever, a ratchet wheel secured to the drum, a pawl for the ratchet, and a lever pivoted between the pawl and the pattern device 5 having a follower for the pattern device and adapted to actuate the pawl.

7. In a straight knitting machine, carrier rods, a narrowing carriage, a pattern device including a variable-link pattern chain, a bracket on the 10 narrowing carriage, elongated carrier-rod stops above the carrier rods longitudinally slidably mounted on the bracket transversely to the rods, the bracket having a slideway for receiving ends of the rods beyond the stops, tension springs provided one connected between each stop and the bracket biasing the stop downwardly toward the corresponding carrier rod, rod contact members 15 adjustably mounted on the front sides of the stops, shoulders on the rear sides of the stops, 20 interchangeable levers pivoted on the bracket each having an arm cooperating with one of said shoulders for raising and lowering the associated stop, adjustable means for limiting the downward movement of the shoulder-engaging lever 25 arms, a drum rotatably mounted on the bracket having portions for detachably receiving buttons provided at least one each for any selected number of stops and each for mounting at any one 30 of a plurality of positions for engaging the other arm of the associated lever, a ratchet wheel secured to the drum, a pawl for the ratchet, a lever pivoted between the pawl and the chain having a follower for the chain and adapted to actuate the pawl to rotate the drum in one direction, and means for preventing reverse rotation 35 of the drum.

MAX RICHTER.
